ANCHORING MEANS FOR DECOYS

William Hoberg, Green Bay, Wis.

Application May 2, 1933, Serial No. 669,038

17 Claims. (Cl. 43—3)

This invention relates to water anchors of the type used to moor floating objects, and has particular reference to a construction suited for use in connection with duck decoys and the like.

- 5 The essential objects of the invention are the provision of a construction of compact form which will not be readily dislodged or allow drifting of the moored object and means associated with the anchor for carrying the attaching line.
- 10 In its application as a decoy anchor, provision is also made whereby the anchor may be conveniently secured to the decoy for transportation purposes.

In the accompanying drawing I have illustrated 15 one embodiment of my invention incorporating novel features of construction and wherein:

Fig. 1 is a top plan view;

Fig. 2 is a side view particularly illustrating the position of my anchor as the attaching line 20 is played out therefrom;

Fig. 3 shows the manner in which my anchor may be associated with the neck of a decoy;

Fig. 4 illustrates my anchor in operative position; and,

25 Fig. 5 is a fragmentary view of a modification. The anchor proper will be formed of lead or iron, as conventionally, and made squat and substantially of cone shape. Whereas, however, the usual mushroom construction includes a spherical rounded undersurface which will cause the anchor to seat generally upright in the soft bed under water, I propose to make my anchor 10 with an undersurface which is rather squat and cone-shaped, providing a peripheral edge 11 at its upper extremity. The purpose in this connection is to cause the anchor to tip as shown in Figure 4, so that the edge portion 11 will exercise a gripping engagement with the water bed, thus to prevent the anchor from sliding along and allowing drifting of the object moored thereby. To further prevent side slip of the anchor, its undersurface can be made of irregular contour comprising a plurality of circumferential areas between its top and bottom of different slope. An outstanding circumferential rib 12 may be included. Such a surface, particularly when the anchor is on a soft bed, will tend to resist lateral movement and, because of the inclined nature of the surface, the peripheral edge will be brought into a position where it will tend to dig into the bed when the floating object moored by the anchor tends to drift.

When used in association with decoys, anchors 55 are usually secured thereto by an attaching line which fastens to a screw-eye or the like on the underside of the decoy so that the attaching line will not appear above the surface of the water. Since the depth of water varies so considerably it is essential that provision be made whereby the length of the line attaching the decoy to the an-

chor can be varied. To accomplish this purpose I propose to provide a reel in association with the anchor upon which the line may be wound when the anchor is not in use and from which it may readily be played out merely by dropping the anchor and decoy into the water. As soon as the anchor reaches the bottom the playing out of the line will stop and any surplus line will remain conveniently in position on the reel. To prevent accidental further unwinding of the line, means is 10 provided whereby after the desired length of line has once been determined the line may be secured.

Associated with the upper side of the anchor is a framework preferably comprising stiff but resilient wire, the lower ends of which may be embedded in the anchor element 10. Such framework is formed to provide portions serving different functions as will be described. Adjacent the anchor the wire frame is formed with spaced parallel portions 13 which will provide a reel upon which the attaching line 14 may be wound as shown in Figures 2 and 4. While it is not essential that the reel portion of the frame be located immediately adjacent the upper surface of the 25 anchor, this is desirable as it will provide a side for the reel.

The frame also provides an enlarged open portion 15 which, as shown in the drawing, may be located adjacent the reel portion, the two sides of the wire being bent outwardly beyond the reel portion 13 as shown. Preferably, the portions 16 incline away from the reel so as to permit the ready unwinding of the line from the reel in the manner shown in Figure 2. The enlarged loop portion 15 of the frame is completed by bending the wire sides inwardly at 18. The purpose of the enlarged loop is to enable the anchor to be secured to a decoy by slipping the same over the neck 17 of the decoy as illustrated in Figure 3. The loop 15 will be formed of such size and shape as to readily slip over the neck of the decoy. Preferably, and as shown, it will be of elongated character so that it may be slipped over the neck and then turned through ninety degrees to bring the narrower portions of the loop into resilient clamping engagement. In Figure 3 the position of the anchor when the loop is slipped over the neck of the decoy is illustrated in dotted lines. By rotation the narrower portions of the loops 16 and 18 are then brought into clamping engagement with the neck 17 of the decoy which is conventionally of elongated character.

In the construction shown the line will not tend to play out from the reel after the anchor has once assumed the position on the bottom shown in Figure 4, since the side portions 16 of the loop 15 will tend to snag the line. However, it is desirable that the attaching line engage the frame at some distance above the anchor 10 so 60

that any tendency of the decoy to drift will tend to cause the edge of the anchor to dig more firmly into the bottom. To this end the wire frame is twisted into a small loop 19. This will 5 provide a point for securing the extremity of the line in fixed position. When all of the line is unwound from the reel and in use, the line will extend directly upwardly through the water from the loop 19. Again, where only part of the 10 line is unwound from the reel and in use, the line extending upwardly from the reel may be snagged by a half-hitch around the loop, as shown in Figure 4. By this arrangement the line is positively held against accidental unwinding from the reel and the connection between the decoy and the anchor is sufficiently far removed from the anchor as to cause a digging in action of the anchor edge when the decoy moves laterally.

20 Instead of snagging the line from the reel at the connection between the loops 18 and 19 as shown in Fig. 4, the loop 19 may be modified to serve the same purpose and enable the line to the decoy to be quickly adjusted to any desired 25 length. Thus as shown in Fig. 5, the loop 21 may be provided with a depending tongue 22, about which a loop or knot in the line may be readily formed and removed at will.

It will be understood that the embodiment of 30 my invention herein shown and described is merely illustrative and that the invention is capable of a considerable range of modification, equivalency and rearrangement of parts without departing from the scope thereof. I therefore 35 do not intend to be limited in the practice of my invention further than may be required by the appended claims.

I claim:

1. An anchor having a sloping undersurface 40 and being of greater thickness at its center than at its edge portion, the undersurface being divided into a series of successive concentrically arranged bands wherein one band is angularly arranged to the next band so as to provide an 45 irregular contour and resist lateral movement of the anchor over a soft surface.
2. An anchor having its sloping undersurface provided with continuous circumferentially extending projections adapted to resist lateral 50 movement of the anchor over a soft surface.
3. An anchor having a sloping undersurface and being of greater thickness at its center than at its edge portion, said anchor having an undersurface provided with one or more circumferentially extending ribs adapted to exercise gripping 55 engagement with a soft surface.
4. An anchor having a squat cone-shaped undersurface provided with one or more circumferentially extending ribs adapted to exercise a 60 gripping engagement with a soft surface.
5. An anchor having a squat generally cone-shaped undersurface of gradual slope, said undersurface having circumferentially extending continuous portions of varying slope between 65 its upper and lower limit to provide an irregular contour which will resist lateral sliding movement of the undersurface over a soft surface.
6. An anchor presenting a flat upper surface and a tapering undersurface and having line 70 attaching means secured to its upper side providing a reel upon which surplus line can be

supported and including line engaging means adapted to prevent unwinding of line from the reel.

7. An anchor presenting a flat upper surface and a tapering undersurface, and having line 5 attaching means secured to its upper side comprising an upstanding wire frame providing a reel upon which line can be wound.

8. An anchor presenting a flat upper surface and a tapering undersurface, and having line 10 attaching means secured to its upper side comprising an upstanding wire frame, said wire frame providing a reel upon which line can be wound and having a line engaging loop at its upper end.

9. An anchor for decoys including an anchoring portion having an upstanding frame extending upwardly from its upper side adapted to slide over and engage the neck portion of the decoy.

10. An anchor for decoys including an anchoring portion having an upstanding resilient wire frame extending upwardly from its upper side adapted to slide over and resiliently engage the neck portion of the decoy.

11. An anchor for decoys including an anchoring portion having an upstanding resilient wire frame extending upwardly from its upper side, said frame having an enlarged portion adapted to slide over and engage the neck of the 30 decoy.

12. An anchor for decoys having an upstanding resilient wire loop connected with its upper surface, said loop being elongated to allow the same to be freely slipped over the neck of the decoy and adapted to be turned when in position so that the narrower portions of the loop will resiliently engage the decoy and secure the anchor in association therewith.

13. An anchor for decoys having line engaging 40 means secured to its upper side, said means including a reel upon which line may be wound and an enlarged wire loop adapted to slide over and engage the neck of the decoy.

14. An anchor for decoys having an upstanding wire frame providing a reel upon which an attaching line may be wound and having an enlarged portion in the form of a loop adapted to slip over the neck of the decoy.

15. An anchor for decoys having an upstanding wire frame providing a reel upon which an attaching line may be wound and having an enlarged portion in the form of a loop adapted to slip over the neck of the decoy, and a small loop formed at the upper end of the wire frame constituting line engaging means.

16. An anchor for decoys having an upstanding wire frame secured to its upper surface, said frame being formed with spaced parallel portions next the anchor providing a reel upon 60 which line may be wound, the frame being enlarged adjacent the reel to form a large loop adapted to slip over the neck of the decoy and being formed at its upper end into a small loop adapted to engage the line.

17. A cone-shaped anchor wherein the sloping undersurface is divided into successive concentric zones, the inclination in one zone differing from that in the next zone.
